DESIGN FOR A SHOE OR SIMILAR ARTICLE

Leo Sholtz, New York, N. Y.

Application October 5, 1937, Serial No. 71,967

Term of patent $3\frac{1}{2}$ years

To all whom it may concern:

Be it known that I, Leo Sholtz, a citizen of the United States, residing in New York city, in the county of New York, in the State of New York, have invented a new, original, and ornamental Design for a Shoe or Similar Article, of which the following is a specification, reference being had to the accompanying drawing, forming part thereof.

I claim:

The ornamental design for a shoe or similar article, substantially as shown.

LEO SHOLTZ.
